UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

STOKER

Application filed July 19, 1927. Serial No. 206,887.

This invention relates to stokers, and more particularly to stokers for locomotives and the like.

One of the objects of the invention is the provision of a new and improved trough or fuel conduit for conveying fuel from the tender to the locomotive.

Another object of the invention is the provision of a cast metal trough or fuel conduit for stokers that is provided with a gear box at the rear end and has reinforced sides, pockets for the supporting springs for the angle ring, reinforcing ribs in the bottom, ball joint at the forward end, wheel supports, and anchor lugs for the radius rods, all cast integral with the trough.

Another object of the invention is the provision of a new and improved means for receiving the fuel from the tender and transferring the same to the locomotive.

Another object of the invention is the provision of a detachable crusher whereby the same may be attached at any point along the trough, thereby permitting the troughs to be standardized as to length.

A still further object of the invention is the provision of new and improved conveyor trough or conduit that is rigid in construction, cheap to manufacture, easily attached in position, strong, durable, well reinforced, and that is not likely to become broken, distorted or get out of order.

Other and further objects and advantages of the invention will appear from the following description taken in connection with the accompanying drawings, in which

Fig. 1 is a vertical section of a portion of a locomotive and its tender showing the invention in position thereon, with parts in section and parts broken away;

Fig. 2 is a bottom plan view of a tender showing the invention in position thereon, with parts broken away;

Fig. 3 is a section on line 3—3 of Fig. 1;

Fig. 4 is a section on line 4—4 of Fig. 1;

Fig. 5 is a perspective view of the conveyor conduit;

Fig. 6 is an elevation of the crusher member;

Fig. 7 is an elevation of the crusher mounting;

Fig. 8 is a plan view of the removable crusher support; and

Fig. 9 is a plan view of the crusher.

It has been the common practice in manufacturing conveyor troughs to bend a sheet or sheets of boiler plate to the desired shape and attach the necessary castings by riveting or bolting.

The conveyor trough or conduit is usually substantially V-shape in cross-section in one portion and U-shape or cylindrical at another portion, and comprises two sheets bent to these two forms and connected together by a suitable casting which is riveted to the adjacent ends of the two sheets.

This type of trough or conveyor is objectionable because the rivets will work loose or shear especially in the longer troughs or the connecting castings will break due to the strain or twisting of the trough caused by the crushing and transferring of the fuel.

When the troughs are made from sheet metal they are likely to become either temporarily or permanently distorted by the strains to which they are subjected, and as a result the angle ring that guides the fuel into the trough will not fit properly, and more or less of the fuel will escape between the trough and the angle ring and be lost.

The present invention seeks to eliminate this difficulty by providing a cast trough that may be sufficiently reinforced only at the points necessary, thereby providing a strong and at the same time a comparatively light and rigid trough.

By casting the trough the upper edge of the same can be reinforced to prevent distortion and its inner edge finished to form a straight edge for cooperating with the vertical flange of the fuel angle ring, as will presently appear, for directing the fuel into the trough without loss thereof.

Referring now to the drawings, in which the same reference characters are employed to designate similar parts throughout the description, the numeral 10 designates generally a locomotive having the usual backhead 11 and cab 12. The tender is shown at 13 and is

provided in its floor or bottom wall with an elongated slot or opening 14 through which the fuel passes into the conveyor trough or conduit designated generally by the reference character 15 located beneath said opening as is usual in such constructions.

The stoker mechanism designated generally by the reference character 16 comprises the elevator mechanism 17 and the conveyor mechanism 18, the latter including the conduit 15 and a screw conveyor 19. The conveyor 19 is operated from the rear through the gears 21 and operating shaft 22 in the usual manner. The conduit 15 is supported by a suitable truck comprising the rollers 23 mounted on stub axles 24 rigidly connected to the conduit as will presently appear. The wheels 23 are mounted on suitable tracks 25 as is common in such constructions. An angle member 27 is interposed between the upper portion of the trough and the floor or deck of the tender at each side of said trough.

As shown in Fig. 3 this member is angular in cross-section, its lower flange 28 is adapted to engage within the trough or conduit 15 and its horizontal flange 29 is adapted to engage the lower side of said deck. The member is held against the under side of the deck by suitable springs 31 which engage pockets 32 integral with the conduit 15. This member 27 is positioned longitudinally of the tender by the links or radius rods 33 which are pivotally attached at their rear ends to said member as at 34 and are pivotally connected to the conduit or trough as at 35 at their forward ends.

The conduit 15 is preferably cast and comprises the rear or trough portion 36 and the forward or cylindrical portion 37 which terminates in a ball member 38 which is adapted to engage in a corresponding socket 39, see Fig. 1, on the rearward extension 41 of the elevator casing, and to be held therein by a pin 42.

Cast integral with the conduit or casing 15 are the pockets 32 for receiving the springs 31, and the lugs or projections 43 provided with the socket members 44 for receiving the stub axles 24. The lugs or projections 43 are also provided with integral sleeves 45 through which the shaft 22 extends.

Anchoring lugs 46 are cast on each side of the conduit, to which the forward ends of the links or radius rods 33 are pivoted. These lugs are provided with slots 47 for receiving the forward ends of said links or rods and with openings 48 for receiving the pivots 35 for said rods. A gear box 49 is cast integral with the rear end of the conduit. Sleeves 51 and 52 having axial openings therethrough are also cast integral with said box and are adapted to receive the journals of the gear mechanism for operating the screw conveyor.

In order to strengthen the casting, ribs 53 extending longitudinally of the trough and

located in the bottom thereof, may be cast on the inner surface of said trough. These ribs are preferably located at each side of the screw conveyor so that they will not only reinforce the trough but will function to assist in preventing rotation of the fuel. The upper edges of the trough may also be provided with inwardly extending flanges 54 and 55 which may be and preferably are machined to form a straight edge against which the flanges 28 of the member 27 are adapted to engage, whereby fuel will be prevented from escaping from the trough between the flanges 28 and the machined surface.

These flanges not only present a surface that may be easily machined, but they also materially strengthen the trough and prevent any warping or twisting due to the operation of the coal crusher and fuel transferring mechanism.

Owing to the expensive patterns necessary for making different lengths of troughs, it is desirable that the length of the trough be standardized, and for this reason neither the coal crusher nor its support is cast integral with the trough. In many instances the same length of stoker may be employed on different types of locomotives. The position of the coal gate varies in the different types of tenders, and since it is desirable that the crusher shall be located just forwardly of the coal gate it follows that by making the crusher and support as separate elements they may be attached to the trough at different points, as the particular installation may require.

In conveying fuel through the stoker conduit the clogs or jams occur at the crusher, and any strains or twisting of the trough necessarily occur or have their origin adjacent to the section having the crusher therein. In order that serious damage may not be done to the trough the crusher support is so constructed that it will give way or break before the trough, whereby the repairs may be easily made with a minimum of time and labor.

A suitable crusher support 50, having flanges 56, see Figs. 4 and 7, which are adapted to engage the bottom walls of the conveyor conduit and be attached thereto by suitable fastening means, as the bolts 57, just forwardly of the coal gate 50, is provided. The support may also be provided with the side flanges 58, which are adapted to be attached to the side walls of the conduit 15, whereby the support not only affords means for attaching the crusher, but also materially strengthens or reinforces the walls of the conduit. The crusher 59, having the crusher teeth or projections 61, is of the well known construction, and is attached in the usual manner, its forwardly extending flange 60 being adapted to engage the lug 62 on the support 50, and its lateral extensions 63 being adapted to engage the rearwardly extending flanges 130

64 on said support, as is common in such constructions.

The holes for the means for attaching the crusher are made in the forward end of the 5 trough when the particular installation is determined.

The closure 640 for the gear box 49 is, of course, a separate element. It is provided with a bearing 65 for the rear end of the stub 10 shaft 66, the forward end of which is connected to the rear end of the screw conveyor 19 for operating the same.

With a cast metal conduit any local weakness that may develop may be remedied by 15 changing the molds to reinforce the casting at that particular point, thereby eliminating the use of metal where it is not necessary, and strengthening the parts only at the points where it is necessary.

20 I claim as my invention:

1. A cast steel fuel conveying conduit comprising a V-section formed with an arcuate bottom, a tubular section, a round forward end, a slide support, a gear housing, spring 25 pockets on the upper edge of the section, and a re-enforcing rib inside of the conduit adjacent the arcuate bottom on each side thereof extending lengthwise the conduit cast integral to form a rigid casting.

30 2. A cast steel fuel conveying conduit comprising a V-section, a tubular section, a round forward end, a slide support, a gear housing, spring pockets cast integral to form a rigid casting, and a reinforcing and guide rib inside of the conduit on each side thereof lengthwise of said V-section.

35 3. As an article of manufacture, a cast metal fuel conduit comprising a trough-shaped fuel section and an integral hollow extension 40 at one end of said section, said extension terminating in a ball-shaped member, a plurality of spaced ribs on the inner side of the bottom wall of said section, lugs on the sides of said section, certain of said lugs having recesses therein to form spring seats, an anchoring lug at each side of said section stub axle supporting lugs at each side of said section, one of said lugs being provided with a cored opening extending longitudinally of 45 the trough for receiving the power shaft, and a gear box integral with the rear end wall of said section, said box having a cored opening through which the drive shaft is adapted to extend and a cored opening for receiving a 50 driving stub shaft.

In testimony whereof I affix my signature.
NATHAN M. LOWER.
